UNITED STATES PATENT OFFICE.

SAMUEL GLAXON, OF NEW YORK, N. Y.

COLLAR.

1,170,243.

Specification of Letters Patent. Patented Feb. 1, 1916.

Application filed March 27, 1915. Serial No. 17,444.

To all whom it may concern:

Be it known that I, SAMUEL GLAXON, a citizen of the United States, residing at New York, in the county of New York and State 5 of New York, have invented new and useful Improvements in Collars, of which the following is a specification.

This invention relates broadly to improvements in turn-down collars, and has 10 specific reference to what are popularly known as soft turn-down collars as distinguished from stiff collars which are so rendered by being impregnated with starch prior to the ironing thereof.

15 The general object of the invention is to permanently incorporate with a soft turn-down collar an attachment which, when properly adjusted, will operate to prevent the spreading of the meeting edges of the front fold of the collar and thereby maintain the soft collar, while in use, in an up-standing position and snugly fitting around the knot of the tie. And to this end the invention resides in substituting for the usual 20 links heretofore employed for connecting the meeting edges of a soft turn-down collar, a pair of tabs applied to the edge portions of the turned over flange of the collar and at the ends thereof, and in having the said 25 tabs provided with button holes arranged so as to register with the button holes in the neck band of a collar when these are connected to the collar button so that the button holes of the tab may readily receive the 30 front collar button which extends through the button holes of the neck band of the collar.

35 In the accompanying drawing: Figure 1 is a perspective view of the collar showing a tie applied thereto. Fig. 2 is a perspective view of the end portions of the collar.

The collar comprises a neckband 1 which is provided in the vicinity of its ends with the usual button-holes 2. An outer fold of 45 material 3 is connected with the upper edge of the neckband 1 in any suitable manner and is adapted to lie along the outer side of the said neckband when the collar is in position upon a shirt. Tabs 4 are attached to the 50 ends of the outer fold 3 and extend down from the upper edge of the band 1. The end portions of the tabs 4 project beyond the

ends of the folds 3 and the lower edges of the said tabs are spaced from the lower edge of the fold 3. The tabs 4 are provided with 55 button-holes 5 which are adapted to register with the button-holes 2 when the collar is in position and all of the said button-holes may receive the shank of the same collar button. The button-holes 5 in the tabs 4 lie 60 beyond the ends of the fold 3 and the upper portions of the tabs 4 are located behind the ends of the upper portions of the fold 3. When the collar is applied the button-holes 2 are passed over the shank of a collar button and the scarf 6 is placed in position about the neckband 1 and under the fold 3. The said scarf is then tied at the front of the collar and the tabs 4 are passed down under the fold and the button-holes 5 are passed 70 around the shank of the collar button. Therefore it will be seen that the bow of the tie is held in proper position at the front of the collar and the end portions of the fold 3 are held in snug toward the neckband and 75 the presence of the said tabs upon the ends of the fold have a tendency to prevent the fold from wrinkling or curling while the collar is being worn. Furthermore it will be seen that means is provided for securely 80 holding the end portions of the fold without using links or similar devices exposed to view. Furthermore it will be seen that the structure of the collar is simple and therefore it is cheap to manufacture and may be 85 readily laundered by machinery usually employed for this purpose.

Having described the invention what is claimed is:—

A collar comprising a neckband and an 90 outer fold, the neckband being provided with button-holes located in the vicinity of its ends, tabs attached to the end portions of the fold and projecting beyond the ends thereof at points between the upper and 95 lower edges of the fold, said tabs having button-holes adapted to register with the button-holes in the neckband.

In testimony whereof I affix my signature in presence of two witnesses.

SAMUEL GLAXON.
